FRONT PANEL FOR AN ELECTRIC CAN OPENER

Henry J. Talge, Kansas City, Mo., assignor to Dazey
Products Company, Kansas City, Missouri, a corpora-
tion of Missouri

Filed Nov. 29, 1967, Ser. No. 9,576

Term of patent 14 years

(Cl. D95—2)

FIG. 1 is a front elevational view of the front panel for an electric can opener showing my new design; and

FIG. 2 is a sectional view taken on line 2—2 of FIG. 1.

My design invention resides in those portions shown in full lines, the dotted line showing being for purposes of illustration only.

I claim:

The ornamental design for a front panel for an electric can opener, as shown and described.
